UNITED STATES PATENT OFFICE

GLENN B. COWLES, OF WESTFIELD, MASSACHUSETTS, ASSIGNOR TO THE H. B. SMITH COMPANY, OF WESTFIELD, MASSACHUSETTS, A CORPORATION OF MASSACHUSETTS

GRATE BAR

Application filed June 30, 1932. Serial No. 620,148.

This invention pertains to grate bars for fuel burning apparatus, for example, house heating boilers or the like, and relates more particularly to a rocking grate bar adapted to be rocked about a fixed axis for discharging ashes, clinkers, etc. In one common form of grate bar a continuous web or support extends from end to end of the bar, such web being suitably shaped adjacent to its ends to provide sockets, pintles, or the like for engagement with appropriate supporting means, and being usually provided with a crank arm or equivalent device which is connected to suitable means for rocking the bar.

10 The longitudinal web or support carries a series of spaced segments whose curved upper edges collectively constitute the fuel supporting surface of the grate bar, such curved upper edges commonly being toothed to provide ash feeding means adapted to grip the ashes and clinkers and to force them downwardly and crush them as the grate is rocked.

In the operation of house heating furnaces, where careful or constant supervision is unusual, there is a tendency for the fire to die out at the edges of the fire box where the fuel comes into immediate contact with the cool side walls, and thus it is common to encounter hard pieces of unburned fuel, 25 calcined lumps of slate, or other incombustible material at points adjacent to the ends of the grate bars. Thus, when the grate bars are rocked to discharge the ash, the end portions of the grate bar encounter these harder 30 and more difficultly frangible materials, so that the ends of the bars are subject to excessive stress and are frequently chipped or broken.

One object of the present invention is to provide a grate bar of the above type having its end portions so reinforced as to enable them to withstand the excessive stresses produced as above referred to, while at the same time to provide additional ash feeding means 45 at these parts of the bar adapted effectively to cut or break lumps of unconsumed material. To this end I unite several of the end-most segments, for example three such segments, at points adjacent to the lower edges 50 of the segments, by means of webs or ribs

preferably integral with the segments, and which preferably form integral continuations of the lowermost teeth of the segments, thus not only providing the desired strength at this point, but also providing additional tooth surface where it is most needed. At the same time, throughout the main body of the grate, the spacing of the segments is preserved to enable the ashes to drop freely between the segments, and the grate bar is not unduly increased in weight, since the strengthening ribs or teeth are confined to those parts of the bar where increased strength is most essential.

In the construction of grate bars of the type in question, it is desirable to provide for free fall of ashes, clinkers, etc., between the several segments, and to facilitate this action I not only confine the strengthening ribs to those parts of the grate bar where most necessary, but I also prefer to taper the body portion of each segment from its upper or curved edge inwardly, and to form the teeth upon a peripheral rim which is substantially thicker laterally than the upper and thickest part of the body of the segment. Thus any ash which is able to pass between the rim portions of adjacent segments finds a constantly widening space in which to fall freely without danger of clogging or choking.

In the accompanying drawing I have illustrated one desirable embodiment of my invention by way of example, and in the drawing,

Fig. 1 is a fragmentary vertical section, extending from front to rear, of a heating device of conventional type showing my improved grate bar installed therein;

Fig. 2 is a side elevation to larger scale showing one of my improved grate bars;

Fig. 3 is a vertical section on the line 3—3 of Fig. 2;

Fig. 4 is a section on the line 4—4 of Fig. 2; and

Fig. 5 is a section to larger scale substantially on the line 5—5 of Fig. 4.

Referring to the drawing, Fig. 1 illustrates the lower part of a house heating boiler of a common type having the front and rear ash

pit walls 1 and 2 respectively, and the front, intermediate and rear boiler sections 3, 4 and 5 respectively, whose lower parts define the combustion chamber. The bottom of this combustion chamber consists of a grate comprising the grate bars 6, which may be supported in any usual manner, for example upon the side walls of the ash pit, so as to rock about their points of support. As shown, alternate bars are connected by means of links 7 to a shaker lever 8 at the front of the heater,—the other alternate set of bars being connected at the other side of the ash pit by similar links, not shown, which in turn are connected to a second shaker lever.

In accordance with the present invention, each grate bar comprises an elongate web or supporting member 9 having enlargements 10 (Fig. 2) at its opposite ends, such enlargements being furnished with notches 11 (Fig. 3) adapted to receive supporting lugs or pins upon which the bar is adapted to rock. Each bar is also preferably furnished with an integral arm 12 (Fig. 2) extending downwardly from the web 9, such arm having a sleeve 13 at its lower end for the reception of a pin 14 connecting it to one of the actuating links 7, all in usual manner.

Each web 9 carries a series of spaced segments S (Fig. 2), preferably integral with the web 9, the series extending substantially from one end to the other of the member 9. Each of these segments preferably comprises a body portion 15 (Figs. 4 and 5), which, in the preferred construction, tapers in thickness from its outer or curved edge inwardly, and whose curved outer edge is preferably thickened laterally to provide a rim 16. As here shown, this curved rim is of substantially 180° extent, although the extent of this rim circumferentially may be varied in accordance with circumstances.

The curved rim of each segment is preferably notched, as indicated at 17 (Fig. 3), to provide a series of teeth 18. Preferably these teeth are of unsymmetrical shape in vertical section, the upper faces of the teeth, particularly at the upper part of the segment, being nearly horizontal, while their outer faces are nearly vertical so as to furnish means well adapted for feeding the ashes downwardly as the grate bar is rocked.

Preferably the lowermost tooth 18^a at each side of each segment is extended continuously from one segment to the next so as to form a continuous cutting edge at that part of the bar which comes most nearly in contact with the next adjacent bar, this being a point at which ash cutting action is highly desirable. This continuous tooth also strengthens the grate bar and prevents chipping of the lower ends of the segments.

As above noted, the end portions of the bars are more subject to breakage and chip-

ping than their middle parts, as at their ends the bars encounter more unburned material than at their center portions, so that the ash cutting and feeding action is desirably most pronounced at the ends of the bars. For this reason, several of the teeth at each side of each endmost group of segments of the bar are continuously united as shown at 18^b. I find in practice that if three of the segments are thus united by several continuous teeth 18^b, sufficient strength is imparted to prevent undue breakage or chipping. In fact, if even two endmost segments are thus united, the added strength is sufficient for many purposes, although as a matter of general practice and to insure sufficient strength for all purposes, I prefer thus to unite the three endmost segments, but this reinforcing is confined to the end groups of segments to avoid interference with the free passage of air and ash through the grate.

While the endmost segments are thus united by two continuous teeth 18^b above and in addition to the lowest teeth 18^a, I contemplate that more than two such additional teeth may be thus made continuous across the segments making up such end groups, although it is preferable, and in fact substantially necessary, to leave the upper parts at least of these endmost segments with spaces between their rims in order to avoid clogging of the grate at its ends. The added strength thus provided at the points where it is most needed is obtained in a very simple way and without adding unduly to the weight of the grate bar and without substantially interfering with the free dropping of the ashes between the segments. At the same time the cutting of the ash and its positive downward feed is provided for in a very efficient and practical manner.

While I have illustrated one desirable embodiment of the invention by way of example, I wish it to be understood that the invention may be embodied in specifically different constructions and that the invention is intended to include all equivalents falling within the scope of the appended claims.

I claim:

1. A grate bar of the class described having an elongate member provided adjacent to its ends with means engageable with supports on which the bar may rock, said elongate member carrying a series of spaced parallel segments whose curved edges collectively constitute the fuel supporting surface of the bar, the curved edge of each segment being notched to define a series of ash feeding teeth, a plurality of the lowermost teeth of a group of segments at each end of the bar extending continuously across from one segment to the next of such group, whereby to brace and strengthen said end segments and to provide adequate ash feeding means at the end portions of the bar.

2. A grate bar of the class described comprising an elongate member provided adjacent to its ends with means engageable with fixed supports on which the bar may rock, said elongate member carrying a series of spaced parallel segments whose curved edges collectively constitute the fuel supporting surface of the bar, the body portions of the several segments tapering in thickness from their curved edges inwardly, the curved edge 10 of each segment being laterally thicker than the body of the segment to form a stiff and strong rim, said rim being provided with a series of ash feeding teeth, the three lowermost teeth of the three endmost segments at each end of the bar extending continuously across from one segment to the next, whereby to brace and strengthen said end segments and to provide adequate ash feeding means 15 at the ends of the bar.
- 20 3. A grate bar of the class described comprising an elongate member provided adjacent to its ends with means engageable with fixed supports on which the bar may rock,

said elongate member carrying a series of spaced parallel segments whose curved edges collectively constitute the fuel supporting surface of the bar, the curved edge of each segment being provided with a series of ash feeding teeth, the lowest tooth of each segment at each side of such segment being integrally united with the corresponding tooth of the next adjacent segment so as to extend longitudinally from one segment to the next throughout the length of the bar, thereby to provide a stiff and strong ash cutting edge, and a plurality of additional teeth, above such lowermost teeth on at least two of the endmost segments at each end of the bar, 70 extending continuously from one such segment to the next, whereby to brace and strengthen such endmost segments and to provide adequate ash feeding means at the ends 75 of the bar.

Signed by me at Westfield, Massachusetts,
this 28 day of June, 1932.

GLENN B. COWLES.
